UNITED STATES PATENT OFFICE

JAY C. HORMEL, OF AUSTIN, MINNESOTA, ASSIGNOR TO GEO. A. HORMEL COMPANY, OF AUSTIN, MINNESOTA, A CORPORATION OF DELAWARE

DESIGN FOR A FOOD CONTAINER

Application filed February 21, 1929. Serial No. 30,166. Term of patent 14 years.

To all whom it may concern:

Be it known that I, JAY C. HORMEL, a citizen of the United States, residing at Austin, in the county of Mower and State of Minnesota, have invented a new, original, and ornamental Design for Food Container, of which the following is a specification, reference being had to the accompanying drawing forming a part hereof.

In the illustration, Fig. 1 and Fig. 2 are perspective views of a food container embodying the design.

What I claim is:

The ornamental design for a food container substantially as shown.

JAY C. HORMEL.
